US0D1080371S

(12) **United States Design Patent** (10) Patent No.: **US D1,080,371 S**
 Feesl et al. (45) Date of Patent: ** Jun. 24, 2025

(54) CLIP FOR VISE ACCESSORIES	2,774,563 A	12/1956	Pribis
(71) Applicant: New Revo Brand Group, LLC , Plymouth, MN (US)	2,778,257 A	1/1957	Linskey et al.
	2,877,689 A	3/1959	Pribis
	2,907,238 A	10/1959	White
	2,948,172 A	8/1960	Gustav et al.
	3,322,423 A	5/1967	Anatoliy et al.
(72) Inventors: Mike Feesl , Inver Grove Heights, MN (US); Ryan Jacobson , Andover, MN (US)	3,463,479 A	8/1969	Hennessey
	3,718,327 A	2/1973	Nunez
	3,783,548 A	1/1974	Fisher
	3,984,092 A	10/1976	Fitzpatrick
	4,070,011 A	1/1978	Glessner
(73) Assignee: New Revo Brand Group, LLC , Maple Grove, MN (US)	4,184,667 A	1/1980	Alessio
(**) Term: 15 Years	4,252,305 A	2/1981	Pasch
(21) Appl. No.: 29/869,240	4,333,132 A	6/1982	Paley
(22) Filed: Dec. 27, 2022	4,333,385 A	6/1982	Culver
(51) LOC (15) Cl. 08-08	4,437,654 A	3/1984	Chiappetti
(52) U.S. Cl. D8/395	4,438,913 A	3/1984	Hylla
(58) Field of Classification Search	4,548,392 A	10/1985	Rickling
USPC D8/14, 21, 27, 70, 75, 86, 88, 394, 395, D8/396, 397; D15/139; D13/173; D2/641	4,569,530 A	2/1986	Cross

(57) CLAIM

The ornamental design for a clip for vise accessories, as shown and described.

DESCRIPTION

FIG. 1 is a left side view of a clip for vise accessories showing our new design;

FIG. 2 is a rear perspective view of the clip;

FIG. 3 is a front perspective view of the clip;

FIG. 4 is a front view of the clip;

FIG. 5 is a right side view of the clip;

FIG. 6 is a bottom perspective view of the clip;

FIG. 7 is a rear view of the clip;

FIG. 8 is a top view of the clip;

FIG. 9 is a bottom view of the clip;

FIG. 10 is a top perspective view of the clip having a light holder vise accessory;

FIG. 11 is a bottom perspective view of the clip having a light holder vise accessory;

FIG. 12 is a top perspective view of the clip having a magnifying glass vise accessory;

FIG. 13 is a bottom perspective view of the clip having a magnifying glass vise accessory;

FIG. 14 is a rear perspective view of the clip having a phone holder vise accessory; and

FIG. 15 is a top perspective view of the clip having a phone holder vise accessory;

FIG. 16 is a side perspective view of the clip connected to a receptacle;

FIG. 17 is a bottom perspective view of the clip connected to a receptacle;

FIG. 18 is a side perspective view of the clip connected to a receptacle;

FIG. 19 is a front perspective view of the clip connected to a receptacle;

FIG. 20 is a side perspective view of the clip connected to a receptacle;

FIG. 21 is a top view of the clip connected to a receptacle;

FIG. 22 is a front perspective view of the clip connected to a receptacle; and,

FIG. 23 is a rear perspective view of the clip connected to a receptacle.

The broken lines of the clip depict parts of the clip that form no part of the claimed design. The broken lines of the vise accessories and receptacles depict the environment and form no part of the claimed design.
